[57] CLAIM

The ornamental design for a railway tie holder, substantially as shown and described.

DESCRIPTION

FIG. 1 is a perspective view of a railway tie holder, showing my new design;

FIG. 2 is a top plan view thereof;

FIG. 3 is a side elevational view thereof;

FIG. 4 is an end elevational view thereof;

FIG. 5 is a bottom plan view thereof;

FIG. 6 is an elevational view of the side opposite that shown in FIG. 3;

FIG. 7 is an elevational view of the end opposite that shown in FIG. 4.

Fig. 1

Fig. 3
